BLOWER FAN

Richard Laupot, New York, N.Y. (½ Universal Metal Chain Co., 75 Clymer St., Brooklyn, N.Y. 11211)

Filed Nov. 26, 1969, Ser. No. 20,284

Term of patent 14 years

Int. Cl. D23—04

U.S. Cl. D23—155

Fig. 2.

Fig. 1.

Fig. 3.

Fig. 4

FIG. 1 is a perspective view of the blower fan showing my new design; and

FIGS. 2, 3, and 4 are, respectively, top, side, and front views thereof.

I claim:

The ornamental design for a blower fan, as shown.
